DESIGN FOR A COMBINED STAND AND INDUCTION DEVICE FOR TELEPHONES

Leland D. Norton, Bridgeport, and Charles Kenneth Wilson, Fairfield, Conn., assignors to Dictaphone Corporation, New York, N. Y., a corporation of New York

Application June 24, 1941, Serial No. 101,642

Term of patent 14 years

To all whom it may concern:

Be it known that we, Leland D. Norton and Charles Kenneth Wilson, both citizens of the United States and residents, respectively, of Bridgeport and of Fairfield, county of Fairfield, and State of Connecticut, have invented a new, original, and ornamental Design for a Combined Stand and Induction Device for Telephones, of which the following is the specification, reference being had to the accompanying drawing, forming part thereof.

The figure shown in the drawing is a perspec-

tive view of a combined stand and induction device for telephones, showing our new design.

The side and end not shown are substantial duplicates of the side and end shown in the drawing.

We claim:

The ornamental design for a combined stand and induction device for telephones, substantially as shown and described.

LELAND D. NORTON.
C. KENNETH WILSON.
